CHECKSTRAP FOR LOOMS

Herbert T. Thrower, Charlotte, and George W. Keesee, Gastonia, N. C.

Application September 22, 1949, Serial No. 117,102

6 Claims. (Cl. 139—161)

1

This invention relates to looms of the kind having a reciprocating shuttle, a picker stick for operating the shuttle and a check strap for arresting the picker stick as the latter approaches the opposite limits of its range of movement, the invention being concerned more particularly in improvements in the check strap.

A conventional check strap supported in operative relation with respect to the associated picker stick is in the form of a loop, being generally elliptical in shape, and surrounding the upper, free end of the picker stick. In swinging back and forth between the opposite limits of its range of movement, the picker stick alternately engages the check strap at the opposite ends of the loop and the movement of the picker stick thereby arrested. As the ends of the loop of a conventional check strap are substantially vertical and as the picker stick is inclined with respect to the vertical in both positions in which it initially engages the ends of the loop, the forces which are to be dissipated are applied substantially in their entirety to the upper edge portion of the check strap, thereby excessively stressing such portion and necessitating frequent replacement of the check strap as a result of localized wear and failure.

The principal object of the present invention, therefore, is to overcome the above objections, this object contemplating a check strap which is so formed that the forces which are to be dissipated are taken up by the check strap in such a manner as to avoid excessive wearing or stressing of local areas and thereby prolong substantially the period for which the check strap will remain effective for its intended purpose.

A further object is to provide a check strap which is so designed that the stresses to which it is subjected by the picker stick during the forward and return strokes of the picker stick will be dissipated in different areas of the check strap.

A still further object is to provide a check strap wherein compensation is made for the more severe action of the picker stick during the forward strokes of the latter.

The invention is illustrated in the accompanying drawings, in which:

Figure 1 is a side elevational view of check strap embodying the features of the invention, the check strap being illustrated in connection with a picker stick and associated loom parts;

Figure 2 is an enlarged view in plan of the check strap, the latter being designed for the left-hand side of the loom and being illustrated in its open, flat condition;

2

Figure 3 is a similar view of a check strap for the right-hand side of the loom; and

Figure 4 is a transverse section taken along line 4—4 of Figure 1.

5 The loom mechanism with which the check strap is associated, and which is illustrated in Figure 1, includes a guide 10, a shuttle 11 which may reciprocate thereon, an oscillating picker stick 12 pivoted to the loom frame, and a contact block 13 which is engaged by the shuttle.

The check strap in which the features of the invention are incorporated is illustrated at 14. As in conventional practice, it is the form of closed loop which surrounds the upper, free end 15 of the picker stick and which is supported in a generally horizontal position by a bracket 15 carried by the guide 10, the loop being elliptical in shape and supported so that the upper end of the picker stick will oscillate along the long axis 20 of the loop as best shown in Figure 4.

In accordance with the invention, the check strap 14 is preferably so formed that, when supported in the manner illustrated, the picker stick 12 will engage the lower edge of the strap as it 25 approaches the limit of the pick stroke (the stroke in which the picker stick drives the shuttle across the loom) while on the return stroke the picker stick will engage the upper edge of the check strap as it approaches the limit of its range of movement in this direction. The check strap thus arrests the picker stick as it approaches each limit of its range of movement and in so doing presents its lower and upper edges alternately so that the forces involved will be dissipated throughout both the upper and lower portions of the strap.

Referring to Figure 1, it will be noted that the right half of the check strap loop is substantially horizontal and that the end wall 16 of the loop 40 is substantially vertical while the left half of the loop curves downwardly so that the end wall 17 is inclined downwardly in the direction of the picker stick. Hence, although the picker stick is inclined in one direction with respect to the vertical when it engages one end of the loop and is inclined in the opposite direction when it engages the opposite end of the loop, it will, as described, engage the lower edge of the check strap during pick strokes and the upper edge of the strap during the return strokes. As the action of the picker stick is more severe on the check strap during the pick strokes, it is preferred that the check strap be so formed that the loop end 17 will be presented to the picker stick at a sharper angle than the end 16. This is clearly shown in 45 50 55

Figure 1 wherein the picker stick is illustrated in full lines at the instant of engagement with the upper edge of the check strap and in dotted lines at the instant of engagement with the lower edge of the strap, it being noted that the angle A which the picker stick makes with the loop end 17 of the check strap is greater than the angle B which it makes with the loop end 16.

The check strap may, as illustrated in Figure 2, be formed from a strip 18 of leather or any other suitable material. For approximately one-half of its length, the strap 18 is straight. The other half of the strap is arcuate, the straight edges of the first half being substantially tangential at the point of juncture with the curved edges of the second half. The opposite ends of the strap may be slotted as indicated at 19 so that the said ends may be joined to form a loop around the picker stick and be attached by suitable fastening means 20 to the bracket 15. In this connection it will be noted that when the ends of the strap 18 are joined and the loop so formed supported in the manner described, the straight end of the strap forms one end of the loop while the curved end of the strap forms the other end of the loop. The curvature of the curved end of the strap may be varied to vary the angle at which the lower edge of the check strap is presented to the picker stick.

From the foregoing it will be apparent that in the operation of the loom both upper and lower edges of the check strap are acted upon by the picker stick. Thereby the stresses set up in the check strap and the wearing action of the picker stick on the check strap are widely distributed so that the development of excessive localized stresses and wear are avoided. It will also be apparent that the straight and curved portions of the strip from which the looped check strap is formed need not necessarily be at the opposite ends of the strip as illustrated, although this is preferred.

In the illustrated embodiment of the invention, the check strap is described as being formed and supported so that the lower edge thereof is engaged during pick strokes of the picker stick while the upper edge is engaged during the return strokes of the picker stick. It will be understood, of course, that this and other features specifically illustrated and described are intended by way of illustration only and that the invention contemplates broadly any form and arrangement of the check strap which will insure alternate engagement of the upper and lower edges of the strap without regard to the character of the stroke of the picker stick at the instant of engagement.

We claim as our invention:

1. A check strap for a picker stick which is movable back and forth between predetermined limits, said strap being in the form of a loop, being adapted to surround said picker stick and being so formed that when supported in its operative position one edge of said strap will be presented to the picker stick when the latter approaches one of said limits and the other edge will be presented when said stick approaches the other of said limits.

2. A check strap for a picker stick which is movable back and forth between predetermined limits, said strap being in the form of a loop,

being adapted to surround said picker stick and being so formed that when supported in its operative position one end extends away from the plane occupied by the other end, whereby said first mentioned end will present one edge of said strap to said picker stick when the latter approaches one of said limits and the other end will present the other edge of said strap when the picker stick approaches the other of said limits.

3. A check strap for a picker stick which is movable back and forth between predetermined limits, said strap being in the form of a loop, being adapted to surround said picker stick and being so formed that when supported in its operative position one end of said loop will occupy a substantially horizontal position while the other end of said loop will curve downwardly, whereby said first mentioned loop end will present the upper edge of said strap to the picker stick when the latter approaches one of said limits and the other of said loop ends will present the lower edge of said strap when said stick approaches the other of said limits.

4. A check strap for a picker stick which is movable back and forth between predetermined limits, said strap being in the form of an elliptical loop, being adapted to surround said picker stick so that the latter will travel along the long axis of the loop and being so formed that when supported in its operative position one end of said loop will occupy a substantially horizontal position while the other end of said loop will curve away from said horizontal position, whereby said first mentioned loop end will present one edge of said strap to the picker stick when the latter approaches one of said limits and the other of said loop ends will present the other edge of said strap when said stick approaches the other of said limits.

5. A check strap of the character described in the form of a flat strip and adapted to provide a loop by connecting the terminal portions thereof, one terminal portion of said strip being straight and the other curved, whereby when said terminal portions are connected the loop thus provided will have one end which curves away from the plane of the other end.

6. A check strap of the character described in the form of a flat strip and adapted to provide a loop by connecting the terminal portions thereof, substantially one-half of said strip being straight and the other half being curved, whereby when said terminal portions are connected the loop thus provided will have one end which curves away from the plane of the other end.
